Attorney

UNITED STATES PATENT OFFICE.

JAMES A. TAYLOR, OF WACO, KENTUCKY.

PLOW.

1,201,649.

Specification of Letters Patent. Patented Oct. 17, 1916.

Application filed October 21, 1914. Serial No. 867,814.

To all whom it may concern:

Be it known that I, JAMES A. TAYLOR, citizen of the United States, residing at Waco, in the county of Madison and State 5 of Kentucky, have invented certain new and useful Improvements in Plows, of which the following is a specification.

This invention relates to new and useful improvements in agricultural implements 10 and more particularly to plows.

The primary object of this invention is the construction of a plow with a means for adjusting the depth of plowing.

Another object of this invention is the 15 provision of a plow having an adjustable clevis.

With these and other objects in view this invention consists in the novel details of construction, combination and arrangement of 20 parts as will be hereinafter described and claimed.

Reference is to be had to the accompanying drawings forming part of this specification, in which similar reference characters 25 indicate corresponding parts throughout the several views, and in which:

Figure 1 is a view in side elevation of a plow with my invention applied, Fig. 2 is a perspective view of the adjustable clevis, 30 Fig. 3 is a longitudinal sectional view of the adjusting mechanism, Fig. 4 is a vertical section on the line 11—11 of Fig. 3, and, Fig. 5 is a detail of the casting.

Referring more particularly to the drawings the numeral 1 indicates a plow beam of ordinary construction having the handles 2 secured to the rear end thereof. Secured to the underside of the beam is the ordinary plow point 3 having the mold board 4 and 35 landside 5, all of the usual construction. A clevis 6 of well known construction is secured to the forward end of the beam and is corrugated on the front face, as shown. Pivotally connected to the beam, at 7, is an adjustable clevis 8 having the upwardly extending portion 9 and this clevis 8 is provided on the forward end with elongated openings 10, which are arranged at a slight angle, as shown. A draft ring 11 is secured 40 to the adjustable clevis by means of a bolt 12 passing through the elongated openings

and when draft is applied the bolt 12 engages the corrugations in the face of the clevis 6. By this construction the strain is placed upon the bolt 12 and old form of 55 clevis and is taken from the pivot pin 7 of the adjustable clevis.

A casting 13 having a longitudinal threaded bore therethrough is secured to the top of the beam 1 and a hollow threaded shaft 60 14 engages and passes through the threaded bore in the casting. A hand wheel 15 is secured on the rear end of the threaded hollow shaft for turning the same. A rod 16 extends through the hollow threaded shaft 65 and is secured in position by means of a nut 17. On the opposite end of the rod 16 is a casting 18 and a rod 19 is connected to the casting and to the upwardly extending portion of the adjustable clevis 8.

It will be seen that by rotating the hollow threaded shaft it moves longitudinally through the casting 13 thereby pulling or pushing upon the rod 19 and raising or lowering the adjustable clevis 8.

Various changes in the form, proportion and minor details of construction may be resorted to without departing from the principle or sacrificing any of the advantages 75 of this invention as claimed.

What I claim is:

In a plow, a beam, a clevis fixedly secured to the beam and coöperating with the fixed clevis, a casting mounted on the beam having a threaded opening therethrough, and 80 exteriorly threaded hollow shaft adjustably mounted in the opening, a rod passing through said hollow shaft, said shaft being rotatable independently of said rod, means to retain said rod and said shaft against 85 relative longitudinal movement, a rod connecting said first mentioned rod and said adjustable clevis, and means to rotate said shaft; whereby longitudinal movement will 90 be transmitted to said first mentioned rod 95 as and for the purpose specified.

In testimony whereof I affix my signature in presence of two witnesses.

JAMES A. TAYLOR.
